(57) **CLAIM**

The ornamental design for a locker handle, as shown and described.

DESCRIPTION

FIG. 1 is a top view of our locker handle;

FIG. 2 is a front view thereof;

FIG. 3 is a bottom view thereof;

FIG. 4 is a right side view thereof;

FIG. 5 is a left side view thereof;

FIG. 6 is a rear view thereof; and,

FIG. 7 is a front perspective view thereof.

Mounting bosses shown in dotted line in FIGS. 1, 3, 4, 5 and 6 form no part of the claimed design.
